Inventor:
Rudolph Jurgenson.

Charles S. Gooding
Atty.

UNITED STATES PATENT OFFICE

RUDOLPH JURGENSON, OF BOSTON, MASSACHUSETTS

REFLECTOR FOR HEADLIGHTS

Application filed August 21, 1928. Serial No. 301,107.

This invention relates to an improvement in reflectors for automobile and other headlights.

The object of the invention is to provide a reflector which will effectively direct rays of light from an automobile or other headlight, a greater portion of said rays of light being reflected forwardly in a horizontal direction; still other rays of light being reflected forwardly and downwardly upon the ground in front of the headlight and a limited number of other rays being reflected forwardly and downwardly to the sides of the headlight.

15 The invention consists in a reflector for headlights as set forth in the following specification and particularly as pointed out in the claims thereof.

Referring to the drawings:

20 Figure 1 represents a front elevation of the reflector embodying my invention.

Fig. 2 is a central vertical section through the reflector taken on the line 2—2 of Fig. 1.

Fig. 3 is a central horizontal section 25 through the reflector taken on the line 3—3 of Fig. 1.

Fig. 4 is a detail section taken on the line 4—4 of Fig. 1.

Like numerals refer to like parts throughout the several views of the drawings.

In the drawings, 5 represents a reflector which may be formed in any suitable manner from sheet material. Viewed from the front, the reflector 5 is circular in form and 35 has a flange 6 extending entirely there-around, and said reflector may be held within any suitable form of headlight casing in any suitable manner.

A greater portion of the area of the reflector 5 comprises a parabolic portion having a reflecting surface 7 from which the rays of light from an electric light bulb 8 will be thrown forwardly in a horizontal direction providing the electric light bulb is 45 properly focused. The electric light bulb 8 is mounted in a socket 9 provided therefor and positioned upon the longitudinal median line of the reflector.

Located a suitable distance above the electric light bulb 8 is a plane reflecting surface

which extends from the front of the reflector rearwardly and downwardly at a slight angle to the longitudinal median line of the reflector. The plane surface 10, furthermore, tapers at its opposite sides at 11 as it extends rearwardly. At the rear of the reflector the plane surface 10 merges into a curved surface 12 which continues downwardly to the center of the reflector. The reflecting surfaces 10 and 12 are provided for the purpose of reflecting rays of light forwardly and downwardly upon the ground in front of the headlight.

Located below the longitudinal median line of the reflector and extending downwardly and forwardly from the lower side of the socket 9 is a ridge 13 having flat inclined sides 14 adapted to reflect rays of light forwardly, downwardly and toward the sides of the headlight.

Also extending radially from the center of the reflector are two other ridges 15 which are shorter than the ridge 13, and these ridges 15 have reflecting surfaces 16 upon their lower sides that are adapted to reflect certain of the rays of light forwardly and downwardly and toward the sides of the headlight.

As a greater portion of the area of the reflector 5 is constructed to provide a parabolic reflecting surface, a greater portion of the rays of light from the electric light bulb 8 will be reflected forwardly as a solid beam of light, providing the electric light bulb is located at the focal point of the reflector. The rays of light that strike the plane and rearwardly inclined surface 10 and the curved surface 12 will be reflected forwardly and downwardly a short distance in front of the reflector and a relatively small number of rays of light striking the ridges 13 and 15 will be reflected forwardly, downwardly and toward the sides of the reflector lighting the roadway at the sides thereof.

I claim:

1. A reflector for a headlight having, in combination, a main parabolic reflecting surface, a plane downwardly and rearwardly inclined reflecting surface above the axis of the reflector and intersecting said parabolic

- surface, and a plurality of ridges having flat inclined sides projecting outwardly from the parabolic reflecting surface below the axis of the reflector and adjacent to the 5 central portion of the reflector and adapted to reflect rays of light emanating from a source of light at the focal point of the reflector downwardly toward the front and sides.
- 10 2. A reflector for a headlight having, in combination, a main parabolic reflecting surface, a plane downwardly and rearwardly inclined reflecting surface above the axis of the reflector and intersecting said parabolic surface, and a plurality of inverted V-shaped ridges having flat sides and extending radially from the central portion of the parabolic reflecting surface below the axis of the reflector and adapted to diffuse rays 15 20 of light emanating from a source of light at the focal point of the reflector and direct the same downwardly toward the front and sides.

In testimony whereof I have hereunto set
25 my hand.

RUDOLPH JURGENSON.
